UNITED STATES PATENT OFFICE

FRITZ TOEWE, OF VILLINGEN, GERMANY, ASSIGNOR TO KIENZLE UHRENFABRIKEN AKTIENGESELLSCHAFT, OF SCHWENNINGEN, GERMANY, A CORPORATION OF GERMANY, KARL WILHELM LANGE, OF BERLIN-WILMERSDORF, GERMANY, AND DEUTSCHER VERSICHERUNGS-VERKEHR A.G., OF BERLIN-DAHLEM, GERMANY, A CORPORATION OF GERMANY

APPARATUS FOR RECORDING THE DISTANCES TRAVELED BY CONVEYANCES

Application filed April 1, 1930, Serial No. 440,697, and in Germany November 20, 1928.

My invention relates to improvements in apparatus for recording the distances traveled by conveyances, and more particularly in apparatus in which cards are stamped in accordance with the mileage traveled and thus later serve as evidence that the conveyance has at no time traveled without a valid card in the device. The object of the improvements is to provide an apparatus of this class which is simple in construction and reliable in operation, and which correctly records the length of way traveled by the conveyance. Another object of the improvements is to provide an apparatus in which after printing the initial mileage reading the card cannot be removed from the outside. With these objects in view my invention consists in constructing the apparatus so that the cards pushed into the same are held therein by a holding device so that they cannot be removed until both the initial and final mileage readings have been effected.

For the purpose of explaining the invention an example embodying the same has been shown in the accompanying drawings, in which the same letters of reference have been used in all the views to indicate corresponding parts. In said drawings,

Fig. 1 is a front elevation of the apparatus, 30 Fig. 2 is a sectional elevation taken on the line 2—2 of Fig. 1,

Fig. 3 is a front elevation of the apparatus with the lid removed,

Fig. 4 is a sectional elevation taken on the line 4—4 of Fig. 2,

Fig. 5 is a sectional elevation taken on the line 5—5 of Fig. 1,

Fig. 6 is a sectional plan view taken on the line 6—6 of Fig. 5,

Fig. 7 is a top plan view of the apparatus with a part of the casing removed,

Figs. 8 and 9 are detail sectional elevations showing the card holding device preventing the card to be removed by non-authorized persons, the said figures showing the apparatus in different positions,

Figs. 10 and 11 are detail sectional elevations showing the card feeding device in different positions,

Figs. 12 and 13 are detail sectional eleva-

tions showing the limit counter in different positions,

Fig. 14 is a diagram illustrating the succession of the operations of the apparatus, and

Fig. 15 is an elevation showing a card having the different readings printed thereon.

In the example shown in the figures the apparatus comprises a casing 1 provided with a tubular foot 1a adapted to be fixed to a suitable part of a vehicle such as a motor vehicle. Within the casing 1 there is a counter 2 showing the mileage traversed by the vehicle at any moment, and a limit counter 3 showing to what limit the card inserted into the apparatus is valid. The counter 2 is always in operation while the vehicle is driving.

The front wall of the casing 1 is provided with a window 4 through which a part of the card 5 is visible on which the length of way traveled by the vehicle is printed. Thus the window shows whether or not a card 5 is within the casing 1, which corresponds to the size of the vehicle and to the rate of the tax or insurance to be paid therefor.

On plates 1c fixed to the rear wall of the casing 1 a rock shaft 7 is mounted by means of which the holding, feeding and printing devices to be described hereinafter are operated, and which is formed with a triangular end 7a adapted to have a key placed thereon for rocking the same, the said key being adapted to be inserted through a tubular stud 6 projecting from the side wall of the casing. The said tubular stud is adapted to be closed by a lid 6a hinged thereto at 6b and formed at its bottom with an eye 6c corresponding to an eye 6e provided on the stud, the said eyes being normally sealed with lead 6d.

The shaft 7 carries cams 8, 9 and 10, 10. The cam 8 is adapted to operate the holding device preventing the removal of the card 5. As shown the said holding device consists of a needle 11 mounted by means of a pivot bolt 11a on a pair of levers 12 and formed with a lug 11b. The levers 12 are rockingly mounted by means of a pivot bolt 12a on a pair of brackets 18a secured to a card holding frame 18. To one of the levers 12 a spring 13 is

attached which is connected with its opposite end to a pin 13a fixed to the plate 1c, the said spring holding the lug 11b of the needle 11 in contact with the cam 8.

- 5 The cam 9 is provided for operating the printing mechanism, and it is engaged by a roller 14a carried by the top ends of a pair of levers 14 (Figs. 5 and 6) rockingly mounted by means of a pivot bolt 14b on the plates 10 1c. Near its bottom end the levers 14 carry a pin 14c by means of which they are jointed to a U-shaped printing slide 15 formed with a slot 15a slidingly engaged by pins 15b secured to the plates 1c. By means of a 15 screw 15c a platen 15d is secured to the slide 15, the said platen being adapted when rocking the slide 15 to press the card 5 onto type wheels 16a of a mileage counter 16 and a plate 17 secured to the plates 1c and having 20 the number of the vehicle engraved or cast thereon. To pins 15e of the arms of the slide 15 springs 15f are connected which are attached with their opposite ends to pins 15g of the plates 1c, the said springs tending 25 to pull the slide 15 forwardly and to hold the roller 14a in engagement with the cam 9.

The cams 10 are formed with two arms, and they are adapted to operate the card feeding device. The said feeding device is 30 connected with the aforesaid card holding frame 18, which frame is vertically shiftable in a guiding frame 33. At its bottom end the said frame is bent angularly so as to provide a shoulder 18d supporting the 35 card 5. At its middle the card holding frame 18 is provided with a cut-out portion 18e (Fig. 3).

The guiding frame 33 is provided with 40 ears 33a secured by screws 33b to the plates 1c. The card holding frame 18 is provided with ears 18b carrying pins 18c adapted to be engaged by the arms 10a and 10b of the cam 10, the arms 10a engaging the said pins from the bottom side thereof for lifting the card 45 holding frame 18 and the card 5 carried thereby, and the arms 10b engaging the said pins for shifting the card holding frame 18 and the card 5 carried thereby downwardly.

The limit counter 3 is mounted on a plate 50 3a secured to an inclined base 3b secured to the casing 1. The said counter is operated from the card feeding mechanism, as will now be described.

To the plate 1c located at the right in Fig. 55 7 a plate 1d is fixed which is perpendicular thereto, and which has a slide 19 vertically shiftable thereon. The flange 19a of the said slide is formed with vertical slots 19b engaged by pins 19c fixed to the plate 1d. For clearness sake the flange 19a provided 60 with the slots 19b is shown in Figs. 12 and 13 in section, while the other flange 19d is shown in elevation.

To a pin 22a fixed to the flange 19a of the 65 slide 19 a spring 22 is connected which is at-

tached with its opposite end to a pin 22b secured to the plate 1d. The flange 19d projects upwardly beyond the flange 19a, and a pin 20 fixed thereto is engaged by the bifurcated end 21a of a lever 21 clamped by means of a screw 21b to the axis 3c of the counter 3.

When moving the card holding frame 18 with a card 5 carried thereby from the position shown in Fig. 12 downwardly and into the position shown in Fig. 13 the lower margin of the said card which is disengaged by reason of the cut-out portion 18e of the card holding frame 18 engages the slide 19 and shifts the same downwardly while putting the spring 22 under tension. Thereby the lever 21 is rocked in clockwise direction thus advancing the limit counter 3 one step, for example from the position shown in Fig. 1 and displaying the figure 500 to the figure 501. When moving the card holding frame 18 and the card 5 upwardly the spring 22 retracts the slide 19 into the position shown in Fig. 12. The limit counter 3 is not operated by the return movement of the lever 21, as is known in the art.

The mileage counter 2 is mounted on a plate 2a secured to an inclined base 2b located within the casing 1 (Figs. 3 and 5). To the shaft 2c of the counter 2 an operating lever 23 is clamped by means of a screw 23b the construction and operation of which is similar to that of the operating lever 21 of the limit counter shown in Fig. 12. When rocking the lever 23 in clockwise direction the counter 2 is advanced in the manner known in the art, and when rocking the lever 23 in anti-clockwise direction the counter 2 is not operated. The lever 23 is provided with a bifurcated end 23a embracing a pin 25a fixed to the downwardly directed arm of a lever 25.

The lever 25 is fixed to a shaft 25b rotatably mounted in the plates 1c. The upwardly directed arm of the lever carries a pin 25c having a pawl 25d mounted thereon, which pawl engages in a ratchet wheel 16b connected with the units type wheel of the set of type wheels 16a of the counter 16.

On a shaft 26 mounted in the plates 1c a cam 26a is mounted, which cam engages a pin 25e fixed to the downwardly directed arm of the lever 25. To the pin 25a a spring 25f is connected which is attached with its opposite end to a pin 25g of the casing, the said spring holding the pin 25e in engagement with the cam 26a. When upon rotation of the shaft 26 in clockwise direction the pin 25e is released from the cam of the disk 26a, the spring 25f rocks the lever 25 in anti-clockwise direction. Thereby the mileage counter 2 is advanced one step through the intermediary of the lever 23. Simultaneously the counter 16 equipped with printing types is advanced one step by means of the pawl 25d.

The shaft 26 is rotated by means of a worm gearing 27 secured thereto and engaged by a

- worm 28a carried by the shaft 28 (Figs. 4 and 5). The shaft 28 is driven by the shaft 29, and the shaft 29 is rotated from a rotary part of the vehicle by means of a flexible shaft (not shown). For recording the length of way of the backward movement of the vehicle a gearing 31, 32 is provided between the shafts 28 and 29 for reversing the said backward movement into forward movement.
- 10 Mechanism of this type is known in the art and I have shown only parts thereof in Fig. 4.
- The card 5 is inserted into the casing 1 through a slot 30 shown in Fig. 2. In the front wall of the casing 1 there are windows 15 3, 4 through which the figures displayed by the counters 2 and 3 may be inspected.
- The operation of the apparatus is as follows: The card 5 is inserted through the opening 30 of the casing 1 and it slides downwardly within the card holding frame 18 until it engages the shoulder 18d provided at the bottom end thereof. After opening the lid 6a a key is passed into the casing through the bore of the tubular stud 6 and placed on the triangular end 7a of the shaft 7. The said shaft is slowly rotated by means of the said key in the direction of the arrow shown in Fig. 8. At first the cam 8 engages the lug 11b thus forcing the needle 11 into the card 5. Thereafter the cam 9 acting on the roller 14a shifts the printing frame 15 through the intermediary of the lever 14, so that the initial reading of the counter 16, for example the number 43760, is printed on the card 5 which for the present is still in the elevated position shown in Fig. 8. After printing the initial state of the counter the card holding frame 18 and the card 5 carried thereby are shifted downwardly into the lowermost position shown in Fig. 11 by means of the arm 10b acting on the top side of the pin 18c (Fig. 10). When moving downwardly into the lowermost position the card 5 engages the slide 19 and shifts the same into the position shown in Fig. 13, so that the limit counter 3 is advanced one step in the manner described above. The card remains in its lowermost position shown in Figs. 11 and 13 until the length of way corresponding to the said card has been traveled by the conveyance. Also the other parts of the apparatus with exception of the mileage counters 2 and 16 remain in their positions during this period of time.
- 55 After the card 5 has been moved into its lowermost position the key is removed from the triangular end 7a of the shaft 7, and the lid 6a is closed and sealed by lead 6d.

After the length of way prescribed by the card 5, for example 1000 kilometers, has been traveled by the vehicle the lead 6d is removed, the lid 6a is opened, and the key is again placed on the triangular end 7a of the shaft 7. Now the shaft 7 is turned in the direction of the arrow shown in Fig. 9 and into

initial position, and by such rotation of the shaft 7 at first the printing frame 15 is operated by the cam 9 and the final reading, say 44760 kilometers, of the mileage counter 2 is printed on the card 5. In addition to the said reading of the mileage counter the number of the vehicle, say 1200, is printed on the card 5, the card 5 having been moved downwardly by the first rotation of the shaft 7 so far that it is in position for being acted upon by the types of the plate 17 (Fig. 5). Now the numbers shown in Fig. 15 have been printed on the card 5. After printing the final reading of the mileage counter and the number of the vehicle the card 5 is released upon further rotation of the shaft 7 in the direction of the arrow shown in Fig. 9 by the cam 8 releasing the lug 11b, so that the needle 11 is retracted by the spring 13 into the initial position shown in Fig. 8 and out of the card 5. At the end of the return movement of the shaft 7 the cam 10a acts on the pin 18c of the card holding frame 18 from the bottom side thereof. Therefore the said card holding frame and the card 5 are shifted upwardly and into initial position. Therefore the card can be taken and retracted from the apparatus through the slot 30. Thus the circuit of the operations is completed, the printed card has been taken from the apparatus, and the apparatus is ready for receiving a new card.

As appears from the foregoing description of the operation, after printing the initial reading of the mileage counter the card 5 is locked against being removed from the guide 18 by the needle 11, and it can be removed from the apparatus only when it has been released by the needle 11 and after printing thereon the final reading of the mileage counter.

In Fig. 14 I have shown a diagram illustrating the operation of the apparatus. The circuit of the operations begins at A and it is continued in the same direction to the point B, wheretupon the direction is reversed to the end C of the operations. At A the card 5 is inserted, and the needle 11 is pushed through the same by turning the shaft 7 through an angle corresponding to the arc a. Now the card is locked within the apparatus. By further rotating the shaft 7 through an angle corresponding to the arc b the initial mileage is printed on the card, and by further turning the shaft through an angle corresponding to the arc c the card is shifted into the lowermost position. By the first part of the return movement of the key through an arc d the final mileage is printed, thereafter by turning the shaft through the arc e, the needle 11 is retracted and the card unlocked, and when turning the shaft through the arc f the card is shifted into initial position. After the shaft has been returned into the position represented by

the letter C the card is taken from the apparatus.

The apparatus described herein may be used for example for controlling the paying of the tax or the insurance of the vehicle or the like equipped with the apparatus, and in this case I may use cards 5 of different appearance according to the size of the vehicle, for example I may use cards of different colors.

If the apparatus is used for controlling the paying of the tax for the vehicle, and an authorized officer removes the seal 6d for replacing the card 5 and turning the shaft 7, the needle 11 prevents the card 5 from being removed by the owner of the vehicle during the period controlled by the card. Therefore, in case of unexpected control of the vehicle the authorized officer can always ascertain if the tax has been paid on the vehicle and what amount has been paid.

In a similar way, if the apparatus is used for controlling the paying of the insurance of the vehicle, and the owner is authorized to replace the card 5 with another one, the needle 11 prevents the card 5 from being removed during the period of the insurance by non-authorized persons.

The needle may be made with different cross-sections showing that a card has been used in the apparatus, and for the same purpose the needle 11 may be provided with type printing certain signs on the card when piercing the same by means of the needle.

As has been explained above, the limit counter 3 is advanced one step when shifting the card 5 into the position for printing thereon the final mileage. Thus the said counter counts the cards inserted into the apparatus. Simultaneously the counter 3 indicates the limit at which a card 5 inserted into the apparatus loses its value, each number of the counter 3 corresponding to a definite limit of the tax or insurance. For example, if the paying of the tax or the insurance begins with the indication of the counter 2 shown in Fig. 1 and displaying the number 43760, the number 501 displayed by the counter 3 corresponds to a tax or insurance period of 1000 kilometers for the limit of 44760 kilometers, the number 502 corresponds to the limit of 45460 kilometers, etc.

If it is desired to read the tax or insurance limit directly from the counter 3, both counters 2 and 3 are set in a similar way at the beginning of the tax or insurance period. The counters are set by known means after opening the casing. For example, it may be assumed that the tax period comprises 1000 kilometers. Now the numeral disk of the lowermost order of the counter 3 indicates the thousands as units. In both counters 2 and 3 at the beginning of the tax period all the numeral disks are reset. If now the first card is inserted into the apparatus, the counter 3

is set on the figure 1, and the owner of the vehicle knows that the counter 2 may be operated while the vehicle is driven from 0 to 1000 kilometers before a new card 5 must be inserted in lieu of the old one. The counter 3 is advanced by the new card to the number 2, so that the counter 2 may now be operated to the mileage 2000, before a new card is inserted.

I claim:

1. A registering mechanism for recording upon a card or series of cards the distance traversed by a vehicle covered by impost or insurance taxes or the like, comprising a casing, an odometer mechanism in said casing adapted to be driven from the vehicle, printing mechanism associated with said odometer mechanism and adapted to print the initial and final odometer readings upon a card inserted into the registering mechanism, a controlling member outside said casing operable at the beginning and at the end of the tax-paid distance to actuate said printing mechanism, said printing mechanism being so disposed within said casing that the card is held completely within the casing during the interval between the initial and final printing, means for retaining said card within said registering mechanism, said means comprising a card holder provided with fixed means to limit downward movement of the card within the card holder, and an element movable against one face of the card to engage the same for preventing the removal of the card from said holder, and means operable after the final odometer reading has been printed on said card to render said engaging element inoperative.

2. A registering mechanism for recording upon a card or series of cards the distance traversed by a vehicle covered by impost or insurance taxes or the like, comprising a casing, an odometer mechanism in said casing adapted to be driven from the vehicle, printing mechanism associated with said odometer mechanism and adapted to print the initial and final odometer readings upon a card inserted into the registering mechanism, a controlling member outside said casing operable at the beginning and at the end of the tax-paid distance to actuate said printing mechanism, said printing mechanism being so disposed within said casing that the card is held completely within the casing during the interval between the initial and final printing, means for retaining said card within said registering mechanism, said means comprising a slidable card holder provided with fixed means to limit downward movement of the card within the card holder, and a cam actuated projecting element pivoted to move against one face of the card to engage the same for preventing the removal of the card from the holder, and cam operated means operable after the final odometer reading has

- been printed on said card to render said engaging element inoperative.
3. A registering mechanism for recording upon a card or series of cards the distance traversed by a vehicle covered by impost or insurance taxes or the like, comprising a casing, an odometer mechanism in said casing adapted to be driven from the vehicle, a control member, means for retaining a card within said casing, said means comprising a slidable card holder and an element movable against one face of the card upon initial actuation of the control member for preventing the removal of the card from said holder, printing mechanism associated with said odometer mechanism and operable upon further actuation of the control mechanism to print the initial odometer reading upon the card, means operable upon further actuation of the control member for sliding said card holder with the card inserted therein, the engaging element following said sliding movement to prevent removal of the card, means operable upon further actuation of said control member for printing the final odometer reading upon the card, and means operable after the final odometer reading has been printed on the card to render said engaging element inoperative.
- 30 4. An apparatus for recording the distance traveled by a vehicle, comprising a slidable record card holder, a key operable member, a pin, means for thrusting said pin into a record card held in said card holder upon operation of said key operable member in one direction, printing numbers driven in relation to the distance traveled by the vehicle, means actuated by further operation in aforesaid direction of said key operable member for printing the initial mileage on said card, means for shifting said card holder together with said pin to place said card in inoperative and locked position during operation of the vehicle, means actuated by movement of said key operable member in reverse direction for printing the final mileage on the card, and means operable after the final mileage is printed for releasing said card and returning it to the initial position.
- 45 5. An apparatus for recording the distance traveled by a vehicle, comprising a slid- able record card holder, a key operable mem- ber, a pin, means for thrusting said pin into a record card held in said card holder upon operation of said key operable member in one direction, printing numbers driven in relation to the distance traveled by the vehicle, means actuated by further operation in aforesaid direction of said key operable member for printing the initial mileage on said card, means actuated by further operation in aforesaid direction of said key operable member for shifting said card holder, card, and pin, while the card remains locked by said pin, means actuated by movement of said key

operable member in reverse direction for printing the final mileage on the card, and means operable after the final mileage is printed for releasing said card and returning it to the initial position.

6. A registering mechanism for recording upon a card or series of cards the distance traversed by a vehicle covered by impost or insurance taxes or the like, comprising a casing, an odometer mechanism in said casing adapted to be driven from the vehicle, printing mechanism associated with said odometer mechanism and adapted to print the initial and final odometer readings upon a card inserted into the registering mechanism, a controlling member outside said casing operable at the beginning and at the end of the tax-paid distance to actuate said printing mechanism, said printing mechanism being so disposed within said casing that the card is held completely within the casing during the interval between the initial and final printing, means for retaining said card within said registering mechanism, said means comprising a slidable card holder provided with fixed means to limit downward movement of the card within the card holder, a shaft, a cam mounted on said shaft, a pivot member, the free end of said member bearing against said cam, a pin carried by said pivot member and adapted to project through one face of the card upon turning of the shaft, for preventing the removal of the card from the holder, and cam operated means operable after the final odometer reading has been printed on the card to render said means for preventing the removal of the card inoperative.

In testimony whereof, I hereunto affix my signature.

FRITZ TOEWE.
